[57] ABSTRACT

Contact arrangement for electrical switching device and electromagnet and armature for alternately moving two switch arms into contact-making and contact-breaking positions. Two spaced contact springs insulated from each other are clamped in a switch housing. A stationary center contact is disposed between the contact springs and has a bifurcated contact end in the form of two legs, one bent tong-like toward one contact spring and the other bent tong-like toward the other contact spring. The two contact springs are biased to engage the stationary contacts and are operated to accommodate one contact spring to engage one stationary contact as the other contact spring is disengaged from the other stationary contact, by a card-like operating member of insulating material carried on the end of the armature. The operating member has a slot intermediate its ends through which one contact spring extends and forms a support at its end opposite the armature for the other contact spring.

ELECTRICAL SWITCHING DEVICE AND CONTACT ARRANGEMENT THEREFOR

FIELD OF THE INVENTION

Contact arrangement for electrical switching devices in which two movable contacts on opposite sides of a rigid stationary contact are operated by a common operating member.

BACKGROUND, SUMMARY AND ADVANTAGES OF INVENTION

Electromagnetic relays have heretofore attained resting and operating contact forces by means of the bias of movable contact springs carrying the movable contacts. Such contact arrangements are called "self-pressure contact arrangements" and are operated in one position by the force of an armature to open one contact and close the other by the bias of the contact spring. Such contact arrangements have a middle contact consisting of a single contact leg with a contact rivet on each side of the leg and disposed between the movable contacts. In such a contact spring set, the contact distances are prescribed by the height of the contact rivet as well as by the dimensions of the operating member for disengaging one movable contact and accommodating the other movable contact to close a circuit. Adjustment of the distances between the movable and stationary contacts with such an arrangement is not feasible in the practical design of a relay and if it were feasible, the best adjustment that can be attained is an adjustment of one space between the stationary and movable contacts at the expense of the space between the other stationary and movable contacts. Moreover, where the middle contact is rigid and single movable contacts are on both sides of the movable contact, the distances between the contacts many times are so close that the leakage paths and air paths between the individual contact carriers are too small for many applications. The interchanging of large contact rivets on the movable contacts for smaller contact rivet does not enlarge the leakage paths and air path to an extent appreciable to make it feasible to attain larger leakage and air paths by the use of larger rivets.

By the present invention, the middle contact is divided into two rigid contact parts tong-like in shape with one contact part spaced upwardly of the center line extending along the points of connection of the contact parts and the other contact part extending downwardly of this center line the same distance as the upper contact. With such contact arrangements, however, two rigid center contacts have heretofore been used requiring the manufacture of two parts, attached separately in insulating member for the contact springs.

By the arrangement of the present invention, a contact switch arrangement is provided in which a single middle contact is carried in the insulating block for the movable contacts and has tong-like stationary contact ends extending upwardly and downwardly of the center line of the middle contact and parallel with each other, with the movable contacts spaced laterally of each other and extending parallel to the part of the middle contact mounted in the insulating base. The two middle contacts are, therefore, generally parallel to the

two movable contact springs on opposite sides thereof.

An advantage of such a design of middle contacts in cooperation with outer, movable contacts is that the distance between the contacts can be adjusted in a simple manner over a far wider range than has heretofore been possible where the stationary contacts are on opposite sides of a single rigid contact member.

A further advantage of the invention is that with the tong-like arrangement of center stationary contacts of the invention, the stationary contacts can be provided with different contacts for specific application purposes and the distance of the contact carriers from each other is increased due to the tong or fork-like arrangement of the stationary contacts, making it possible to use a thicker and more rigid arrangement of stationary contacts than has heretofore been possible.

A further advantage of the present invention is that the transfer of armature movement of the relay to the two movable contacts is by a card-like actuating member made from a relatively thick insulating material and arranged to receive and support the ends of the two movable contacts to provide a stable actuating connection from the armature of the relay to the movable contacts.

The actuating card may be used for a single movable contact as well as for two contacts and when so used, a slot opening into one side of the card extends along opposite sides of the single movable contact and is so arranged that the actuating card may be inserted in the switch housing from its side with the slot spaced in accordance with the required distance between the stationary and movable contacts when disengaged.

This actuating card made from insulating material is further of advantage where the relays are enclosed in box-like housings totally enclosing the free ends of the movable contacts and rendering the free ends of these contacts inaccessible.

Other objects, features and advantages of the invention will be readily apparent from the following description of a preferred embodiment thereof, taken in conjunction with the accompanying drawings, although variations and modifications may be effected without departing from the spirit and scope of the novel concepts of the disclosure.

DESCRIPTION OF THE DRAWINGS

FIG. 1 is a view in side elevation of an electromagnetic relay constructed in accordance with the principles of the present invention with one end wall of the relay removed.

FIG. 2 is a horizontal sectional view taken substantially along line A—A of FIG. 1.

FIG. 3 is a plan view of an actuating card constructed in accordance with the principles of the present invention for insertion between the armature and contact springs from one side of the switch housing; and

FIG. 4 is a top plan view of the card shown in FIG. 3 with the card inverted for inserting from the opposite side of the switch housing.

DESCRIPTION OF PREFERRED FORM OF THE INVENTION

In FIG. 1 of the drawings, I have shown an electromagnetic relay constructed in accordance with the principles of the invention and carried in a housing or casing 1 which may be made of insulating material and

may have a removable side cover 1a secured to the end walls of the casing for detachable connection therewith by means of screws or any other suitable securing means. The relay includes an electrically energizable magnet coil 2 having a yoke 3 mounted at one end thereof and extending along the top of the magnet coil parallel thereto and forming a pivotal mounting for an armature 4. The armature 4 has one leg 4a extending along the core of the coil 2 and a right-angled leg 4b extending parallel to the coil 2 and having a free end having a slot therein for receiving a tongue 5b of a rigid actuating card 5. The actuating card 5 is shown as being relatively thick in comparison with the contacts operated thereby and is made from an insulating material to insulate contacts 6 and 7 from each other as well as move said contacts against their bias. The contacts 6 and 7 are spring-like contacts in the form of elongated contact springs secured to and extending through inwardly extending bosslike supports 7a and 7b formed integrally with the housing 1 and extending inwardly therewith. A rigid middle contact 8 is carried between the bosses 7a and 7b and may be molded in said bosses and includes a shank 8a extending for the length of the bosses 7a and 7b and having a projecting free end which is split tong-like and forms two parallel vertically spaced contacts 9 and 10 spaced laterally of each other and extending parallel to the shank 8a. A terminal 8b extends from the shank 8a through an end wall of the housing 1 and may serve as a solder contact while a terminal 8c extends laterally of the contact 8 through a side wall of the housing and also may serve as a solder contact. The solder contacts 8b and 8c may be arranged in accordance with the direction of installation of the relay and the solder connection 8c extend from the opposite side wall from that shown where the position of the relay during installation is reversed. The contact spring 6 is also provided with two solder connections 6a and 6b. The contact spring 7 may be provided with similar solder connections. The solder connection 7c is the only solder connection herein shown since the other solder connection would be directly beneath the solder connection 6a.

Referring now in particular to the actuator card 5, the contact spring 6 abuts the top of said card as shown in FIG. 3 while the contact spring 7 fits within the slot 11 as shown in FIGS. 3 and 4. The lower contact spring 7 is on the upper surface of the slot 11 during downward movement of the actuator card and thus breaks the circuit between the contacts 7 and 10 and accommodates the bias of the spring contact 6 to complete a circuit between the contacts 6 and 9. In an opposite direction of movement of the armature 4 and leg 4b thereof, the top of the actuator card 5 engaging the bottom of the contact spring 6 will open a circuit between the contacts 6 and 9 and the slot 11 will accommodate the closing of a circuit between the contacts 7 and 10, by the bias of the contact spring 7.

It will be noted from FIGS. 3 and 4 that the bridge 5a of the actuator card is relatively wide in relation to the entire width of the card and thus gives the card sufficient stability to effectively perform its switch opening and closing operations and since the slot 11 opens to one side of the card, the card may be inserted into engagement with the armature and the contact springs 6 and 7 from one side or the other of the switch casing by merely inverting the card. Moreover, the slot 11 opening to one side of the actuator card enables a wide

bridge to be attained in contrast to a slot in the center of the card, necessitating small bridges on opposite sides of the slot, and making it necessary to insert the actuator card from the end of the switch casing rather than from either side thereof. Insertion and removal of the bridge from the end of the switch casing cannot be done without removing an end wall of the casing to accommodate this operation.

Moreover, with the contact card shown affording an actuating connection to the two contact springs 6 and 7, the card has sufficient rigidity to effectively operate over a long period of time and can be fastened to the armature and contact springs in a straight and vertical assembly without requiring the use of screws or other fastening means.

A leaf spring 12 is suitably connected between the yoke 3 and actuator card 5 to serve as a return spring for the actuator card and armature upon deenergization of the coil 2.

I claim as my invention:

1. In an electrical switch and contact arrangement therefor,

a switch casing made from insulating material,
two flat vertically spaced contact springs carried by
said switch casing and insulated from each other by
said casing,
a stationary contact between said contact springs and
insulated therefrom,
said stationary contact having a shank mounted in
the insulating material of said switch casing and
having bifurcated tong-like contact ends spaced
laterally and vertically relative to each other,
each contact end being aligned with an associated
contact spring and being generally parallel to each
other, and

said contact springs being biased towards said
contact ends, and
actuating means for said contact springs, disengaging
one contact spring from its associated contact end
and accommodating the other contact spring to en-
gage its associated contact end by its spring bias.

2. The contact arrangement of claim 1, in which the stationary contact has a one-part shank having a slot extending along the contact end thereof with a contact end on one side of said slot bent upwardly in an angular direction and then bent parallel to said shank, with the contact on the other side of said slot bent downwardly in an angular direction and then bent to extend parallel to said shank.

3. The electrical switch and contact arrangement of claim 2, wherein the actuating means for the contact springs includes,

an electromagnet,
an armature operated thereby and having a portion
extending along the end of said electromagnet and
a right-angled portion extending generally parallel
to said electromagnet, and
an actuator card detachably carried by said electro-
magnet and having operative connection with said
contact springs accommodating engagement of one
contact spring with its stationary contact by the
bias of said spring and having actuating engage-
ment with the other of said contact springs to dis-
engage said contact spring from its associated
contact end.

4. The electrical switch and contact arrangement of claim 3,

wherein the actuator card is wider than the combined width of the two contact springs, and wherein a slot opens to one side of said actuator card for receiving one of said contact springs and so arranged relative to said actuator card as to provide a relatively wide bridge extending along one side of said slot and connecting opposite ends of said card, and accommodating said card to be inserted from

either side of the casing depending upon the position of installation of the switch and casing.

5. The electrical switch and contact arrangement of claim 4, including a return spring returning said armature and actuator card upon deenergization of said electromagnet.
